UNITED STATES PATENT OFFICE.

FRANK P. HARP, OF COLLINWOOD, OHIO, ASSIGNOR OF ONE-HALF TO
ROBERT A. BOWERS, OF CLEVELAND, OHIO; KATE HARP ADMINIS-
TRATRIX OF SAID FRANK P. HARP, DECEASED.

CAR-WINDOW.

No. 833,132.

Specification of Letters Patent.

Patented Oct. 9, 1906.

Application filed July 17, 1903. Serial No. 165,903.

To all whom it may concern:

Be it known that I, FRANK P. HARP, a citizen of the United States, residing at Collinwood, in the county of Cuyahoga and State of Ohio, have invented a certain new and useful Improvement in Car-Windows, of which the following is a full, clear, and exact description, reference being had to the accompanying drawings.

10 My invention relates to means for balancing window-sashes, especially those of car-windows, and has for its general object the provision of means for this purpose which shall combine simplicity and inexpensiveness of construction with efficiency in operation. More particularly its object is the application of a sash-balance to the double windows such as are in ordinary use on Pullman cars without the necessity for other 15 than slight changes in the construction thereof.

The invention may be defined generally as consisting of the details of construction set out in the claims hereto appended.

20 Referring to the drawings, Figure 1 represents a front elevation of my window; Fig. 2, a detail sectional view taken on the line 2 2 of Fig. 1; Fig. 3, an elevation with parts broken away of one of the spring-balances, 25 showing its mode of attachment to the window; Fig. 4, a sectional detail taken on the line 4 4 of Fig. 3; Fig. 5, a detail plan view of the upper spring-balance shown in Fig. 3; Fig. 6, a detail view showing one of the arms 30 by which the sashes are attached to their respective spring-balances, and Fig. 7 a detail view of a portion of the parting-strip.

Referring to the parts by letters, A represents the window, which, as shown, has 35 three sashes B, C, and D. Of these sashes the first two are the sliding or movable sashes, adapted to be raised or lowered, and the last is the stationary upper sash usual in windows of Pullman cars.

40 In order to balance the weight of the sashes B C, I employ two sets of spring-balances, one on each side of the window. Each set includes two spring-reels which are of ordinary construction; but they are combined with each other and with the window in a new way, which will now be pointed out. As these sets of balances are identical in construction and operation and in their

manner of attachment to their respective sides of the window-sashes, it will be necessary 55 to describe but one set in detail, the one on the left-hand side of the window being selected for such purpose. The difficulties that have hitherto existed in the employment of such spring-balances with car-windows are, first, the thinness of the vertical posts or jambs F, which prevents the insertion of the balances within said posts or jambs without materially weakening the same, it being vital that, as said posts or 60 jambs support the roof of the car their strength should not be impaired; second, in the event of any of the balances becoming deranged (an event which is liable to occur frequently in actual service) it is inconvenient to obtain access to said balances in order to repair or renew the same. With the construction of window shown in the drawings and the balances inserted into the jambs it would be necessary to remove the 65 paneling K and the windows before access could be had to the balances. To obviate these difficulties, I have located said balances interiorly of the jambs or posts F and have constructed and combined them with the 70 window as follows: A casing E is adapted to be secured to the parting-bead G between the sashes B and C in any suitable manner, as by screws, so as project outward from said parting-bead into the window-opening. 75 In this casing the two spring-reels e e' are rotatively mounted one above the other, but with the periphery of the upper reel extending nearer to the parting-strip than the periphery of the lower reel. The parting-strip consists of two portions, a solid portion 80 or stop g and an angular hollow portion g', the latter being secured at its upper end to the casing E, as by a bolt g⁴, and at its lower end to the solid portion, as by means of a 85 strap g³. The portion g of the hollow parting-strip carries the pulleys e e', which project into the window-space. This construction is advantageous not only where two sliding sashes B C are employed, but also as is the 90 case with car-windows in ordinary day-coaches, where a single sliding sash, as C, is present. The portion g constitutes a stop for the sash C and at the same time carries either of the pulleys e e' or both of them, according as one or two sliding sashes are em- 95 100 105

ployed. In order to apply said pulley or pulleys to the window, it is only necessary to screw the stop to the window-jamb. If necessary to remove either of the pulleys for the purpose of repairing or renewing the same, it is only necessary to remove the stop, whereupon convenient access may be had to the pulley-frame and pulleys.

On the outer periphery of each of the reels 10 is secured a flexible band $e^3 e^4$, by means of which, in conjunction with the springs in said reels, spring-balances are formed for sustaining the weight of the sashes B and C. The means for attaching these sashes to their respective bands will now be described.

Between the hollow member g' of the parting-strip and the solid member thereof is provided a narrow slot g^2 , said slot being extended up into the body of the casing E. 20 A U-shaped angular arm b , secured to the rear face of the stile of the sash B, projects through this slot and is provided in its lower edge with a hook b' for the reception of a loop e^5 on the band e^3 . From the inner face 25 of the stile of the rear sash C projects a hook c , by means of which said sash is secured to e , by means of which said sash is secured to the band e^4 in a manner similar to that in which the sash B is secured to its band. The arm b and the hook c both extend into the 30 hollow member of the parting-strip.

As heretofore stated, the periphery of the lower spring-reel is further removed from the parting-strip than is that of the upper reel. The purpose of this is to permit the bands of 35 said spring-reels to be attached to their respective sashes and permit said sashes to be raised and lowered without interference between said bands, while the hollow parting-strip inclosing said bands protects them 40 from interference or injury.

As hereinbefore explained, one of the sashes and its associated spring-reel and the connections between them might be omitted without avoiding certain characteristics of 45 invention set forth in the claims.

Having described my invention, I claim—

1. In a window, the combination of a pair of sashes, of a pair of spring-balances for said sashes, said balances being located in a plane 50 intermediate of the planes of the sashes with their peripheries in different vertical planes, substantially as described.

2. In a window, the combination of a pair of sashes, of a pair of spring-balances for said 55 sashes located intermediate of the planes of said sashes, each balance comprising a spring-reel and a peripheral flexible band, the peripheries of said reels being out of vertical alinement, substantially as described.

3. In a window, the combination of an inner and an outer sash, of separate means for 60 balancing each of said sashes, said means being located intermediate of the planes of said sashes and interior to the jamb of the window, one of said balancing means being

nearer to the jamb than the other, and means for connecting said balancing means the one with the inner and the other with the outer of said sashes, substantially as described.

4. In a window, the combination of an inner and an outer sash, of a pair of spring-balances intermediate of the planes of said sashes and interior to the jamb of the window, the upper of said balances being closer to said jamb than the lower, and means extending from each of said balances for connecting the one to the inner and the other to the outer of said sashes, substantially as described.

5. In a window, the combination of a pair of sashes, an upper and a lower spring-balance intermediate of the planes of said sashes and located interior to the jamb of the window, the upper balance being nearer said jamb than the lower, and a flexible connection 85 extending from said balances and connected to said sashes, substantially as described.

6. In a window, the combination of a pair of sashes, a hollow parting-strip between said 90 sashes, a pair of spring-balances carried by said strip, each of said sashes being provided with an attaching device extending within said strip, and flexible connections between said balances and said attaching devices, 95 said connections being located within said hollow parting-strip, substantially as described.

7. In a window, the combination of a pair of sashes, a hollow parting-strip between said 100 sashes having a slot in each side thereof, a pair of spring-balances at the upper end of said strip, each having a flexible band leading therefrom, and an attaching device projecting from each of said sashes through its 105 slot in the parting-strip and connecting with its appropriate band, substantially as described.

8. In a window, the combination of a pair of sashes, a hollow parting-strip between said 110 sashes having a longitudinal slot therein, a spring-balance attached to said parting-strip and projecting within the window-opening, a U-shaped arm projecting from the stile of one of said sashes and extending 115 through the slot in the parting-strip, and a band extending from said spring-balance into the hollow parting-strip and secured to said arm, substantially as described.

9. In a window, the combination of a pair 120 of sashes, a hollow parting-strip between said sashes, said strip consisting of a solid member secured to the jamb of the window and an angular member spaced therefrom, means for securing the lower end of said angular 125 member to the solid member of the strip, a casing secured to the upper portion of the angular member and to the solid member of said strip, spring-balances carried by said casing and provided with flexible connec- 130

tions extending into said hollow space, and means extending from said sashes into said hollow strip for attaching the sashes to said flexible connections, substantially as described.

10. In a window, the combination of a pair of sashes, a hollow parting-strip therebetween, said strip consisting of a solid portion secured to the jamb of the window and an angular portion spaced from said solid portion, means for securing the lower end of said angular member to the solid member, a casing secured to the upper end of said hollow member and to the solid member, a pair of 15 spring-balances carried by said casing above said angular member and each having a flexible band extending into the hollow parting-strip, and means projecting from each sash into the said hollow parting-strip for connecting such sash to its appropriate band, substantially as described.
11. In a window, the combination of a pair of sashes, a hollow parting-strip between said sashes having a slot on each side thereof, upper and lower spring-balances intermediate 25 of the vertical planes of said sashes adjacent to the jamb of the window and interior thereto, the upper balance being closer to said jamb than the lower, a flexible band extending from each of said balances into the hollow parting-strip, and an attaching device carried by each of said sashes extending through the slotted portion of the hollow parting - strip corresponding thereto and 30 adapted to be connected with its appropriate band, substantially as described.
- 35

12. The combination of the window-frame jambs having parting-strips which are partly hollow, and a sliding window-sash, with a spring-balance secured to each parting-strip 40 and projecting therefrom into the window-opening above the hollow part of said strip, the bands of said spring-balances extending downward through the hollow parting-strips, and devices secured to the stiles of the sash 45 and projecting therefrom into said hollow parts of the parting-strips, to which said bands are secured, substantially as described.

13. In a window, the combination of a pair of sashes, a parting - strip therebetween, a 50 spring-balance secured to such parting-strip and projecting into the window-space, an attaching device secured to the stile of one of the sashes, and a band extending from said spring-balance and attached to said device, 55 substantially as described.

14. In a window, the combination of a pair of sashes, of a hollow parting-strip therebetween, means for balancing one of said sashes, said means being attached to the upper portion of said hollow parting-strip, an attaching device projecting from the stile of said sash within said hollow parting-strip, and a connection between said device and the balancing means, said connection being within 60 65 said strip, substantially as described.

In testimony whereof I hereunto affix my signature in the presence of two witnesses.

FRANK P. HARP.
